DESIGN FOR A DOLL CRADLE

Rosa L. Morton, Birmingham, Ala.

Application January 3, 1942, Serial No. 104,981

Term of patent 14 years

To all whom it may concern:

Be it known that I, Rosa L. Morton, a citizen of the United States, residing at Birmingham, in the county of Jefferson and State of Alabama, have invented a new, original, and ornamental Design for a Doll Cradle, of which the following is a specification, reference being had to the accompanying drawing, forming a part thereof.

In the drawing,

Fig. 1 is a perspective view of the doll cradle taken from the rear; and

Fig. 2 is a perspective view taken from the front of the doll cradle.

I claim:

The ornamental design for a doll cradle, substantially as shown.

ROSA L. MORTON.
